BRUSH

Ruth R. Rissler, Sedalia, Mo.

Application April 21, 1952, Serial No. 283,321

2 Claims. (Cl. 15—236)

1

This invention relates to brushes.

An object of this invention is to provide a brush structure embodying circular bristles or cleaning elements which are secured to a head, whereby dishes, forks or other elements may be cleaned.

Another object of this invention is to provide a brush structure wherein the bristles, after performing their cleaning operation, may be cleaned by projecting a water stream through the center of the bristles.

A further object of this invention is to provide a brush structure wherein the bristles are of endless construction, with the bristles arranged in angularly related bristle groups and with the bristles and the brush head, including the handle, formed out of plastic or other similar material.

With the above and other objects in view, my invention consists in the arrangement, combination and details of construction disclosed in the drawings and specification, and then more particularly pointed out in the appended claims.

In the drawing:

Figure 1 is a detailed side elevation partly broken away and in section of a brush constructed according to an embodiment of this invention.

Figure 2 is a detailed end elevation partly broken away of the brush.

Figure 3 is a detailed side elevation partly in section of one of the bristle groups.

Figure 4 is a fragmentary plan view showing one of the bristle groups.

Figure 5 is a fragmentary sectional view taken on the line 5—5 of Figure 3.

Referring to the drawing, the numeral 10 designates generally a brush handle which is formed at its inner or rear end with an opening 13. The handle 10 has secured to or formed integral with the forward end thereof a transversely arcuate brush head 11 having a concave upper side 12. A plurality of groups of bristles generally designated as 14 are secured to and extend from the concave inner side of the brush head 11, and each bristle group is formed of a central circular member 15 with crossed angularly related bristle members 16 and 17. It will be readily apparent that the formation need not be confined to circular and that oval or other shapes may be utilized, the important feature being to maintain an axial opening so that all accumulated matter can readily be flushed off the brush by directing a stream of water therethrough and thus have a sanitary, clean center. An oval shape would be an advantage (for example, in cleaning milk bottles and the like).

The inner or rear portions of the bristle members 15, 16 and 17 are secured to or embedded within the head 11. The axes of the bristle members 15, 16 and 17 are disposed in a plane parallel to the axis of the concave outer side 12 of the head 11. These bristle members 15, 16 and 17

2

may be secured together at their crossing points, as indicated at 18, or if desired the bristle members may be unsecured one relative to the other so that the bristle members may have independent movement in the use of the brush.

In the formation of the brush structure, the bristles 15, 16 and 17 may be secured within the concave side 12 of the head 11 at the time the plastic forming the head 11 is relatively soft, or, if desired, the bristles may be cemented or otherwise firmly attached to the head 11 in the concave forward side 12 thereof.

The brush is used in the conventional manner in the cleaning of dishes or other implements, and when the brush is to be cleaned, the brush may be turned edgewise so that a stream of water may be projected axially through the bristles.

The construction and arrangement disclosed herein makes possible a thorough cleaning of all the tine surfaces when for example, using the device to clean the tines of a fork or the surfaces of a spoon. There may be as many groups of bristles as desired.

I do not mean to confine myself to the exact details of construction herein disclosed, but claim all variations falling within the purview of the appended claims.

What I claim is:

1. A brush comprising a head formed with a concave forward side, a handle projecting from said head, and a series of groups of bristles carried by said head, said bristles being fixed in said concave forward side, each group of bristles being formed of three ring-shaped bristle members arranged in crossed relation the central member of each group lying in a plane perpendicular to the axis of said brush head and the outer members of each group being inclined toward and crossing each other and the central member.

2. A brush having a handle portion and elements forming a brush head secured to said handle, said elements composed of spaced groups of three continuous members arranged in crossed relation the central member of each group lying in a plane perpendicular to the axis of said brush head and the outer members of each group being inclined toward and crossing each other and the central member, to provide an axial clear space therethrough whereby waste material accumulated on said head way be flushed off by a stream of water projected through said space.
